(57) **CLAIM**

The ornamental design for a dispensing system, as shown and described.

DESCRIPTION

FIG. 1 is a front, top, and left side perspective view of the dispensing system showing our new design; FIG. 2 is a front elevational view of FIG. 1; FIG. 3 is a rear elevational view of FIG. 1; FIG. 4 is a left side elevational view of FIG. 1, wherein the right side elevational view is a mirror image of the left side elevational view; FIG. 5 is a top plan view of FIG. 1; and, FIG. 6 is a bottom plan view of FIG. 1.

It is understood that the bounds of the claimed design are represented by shade lines to the end of the solid lines of the container at the bottom end, and by shade lines to the end of the solid lines of the overcap at the top end. The broken lines are included for the purpose of illustrating the portions of the dispensing system that form no part of the claimed design.
